Fig. 3.

Fig. 4.

To all whom it may concern:

Be it known that I, Cecil E. Chesser, a citizen of the United States, residing at Hebron, in the county of Licking and State of Ohio, have invented a new, original, and ornamental Design for a Wheel or Similar Article, of which the following is a specification, reference being had to the accompanying drawings, forming a part hereof.

Fig. 1 is a plan view of one side of wheel or similar article, embodying my new design.

Fig. 2 is an elevational view of the same showing the peripheral and hub portions thereof.

Fig. 3 is a view similar to Fig. 1 but showing the opposite side of said wheel, and

Fig. 4 is a diametrical sectional view of the same. The tire disclosed by means of broken lines in Figures 1 and 3 is shown only for illustrative purposes.

I claim:

The ornamental design for a wheel or similar article, as shown and described.
